(57) **CLAIM**

The ornamental design for a vaporizer cartridge, as shown and described.

DESCRIPTION

FIG. 1 is a bottom perspective view of a first embodiment of a vaporizer cartridge of our design;

FIG. 2 is a top perspective view thereof;

FIG. 3 is a front plan view thereof; the rear plan view is substantially the same;

FIG. 4 is a side plan view thereof; the opposite side plan view is substantially the same;

FIG. 5 is a top plan view thereof; and

FIG. 6 is a bottom plan view thereof.

FIG. 7 is a bottom perspective view of a second embodiment of a vaporizer cartridge of our design;

FIG. 8 is a top perspective view thereof;

FIG. 9 is a front plan view thereof; the rear plan view is substantially the same;

FIG. 10 is a side plan view thereof; the opposite side plan view is substantially the same;

FIG. 11 is a top plan view thereof; and,

FIG. 12 is a bottom plan view thereof.

The broken lines show portions of the vaporizer cartridge that form no part of the claimed design.

1 Claim, 10 Drawing Sheets
